UNITED STATES PATENT OFFICE.

CHARLES E. WILLIAMS, OF WINSTED, CONNECTICUT, ASSIGNOR TO WILLIAM L. GILBERT CLOCK COMPANY, OF WINSTED, CONNECTICUT, A CORPORATION OF CONNECTICUT.

METAL CLOCK.

1,418,895.

Specification of Letters Patent. Patented June 6, 1922.

Application filed February 23, 1922. Serial No. 538,656.

To all whom it may concern:

Be it known that I, CHARLES E. WILLIAMS, a citizen of the United States, residing at Winsted, county of Litchfield, State 5 of Connecticut, have invented a certain new and useful Improvement in Metal Clocks, of which the following is a full, clear, and exact description.

The present invention relates to clocks and 10 more particularly to metal alarm clocks, and has for its object to provide novel and improved means in a clock of this character for holding the dial glass or crystal in place.

15 In the accompanying drawings—

Figures 1 and 2 are rear and side elevations, respectively, of a metal alarm clock embodying the features of the invention in their preferred form; and

20 Fig. 3 is a vertical sectional view taken on the line 3—3 of Fig. 1.

The metal alarm clock illustrated in the drawings is provided with a casing 2 having a forward part 4 of sheet metal in the 25 form of a cylindrical shell, a back cover 6 the forward portion of which is telescopingly received in the rear portion of the shell 4 and is held in place by screws 7 extending through slots in the shell and screw 30 threaded into the telescoping flange of the back cover, and a gong 8 extending over the cover. The clock is further provided with a dial 10 which is supported by legs 11 secured to the clock mechanism frame 12 which in turn is secured to the back cover 6 of the casing. As illustrated the dial 10 is provided with a forwardly extending peripheral flange 14 that fits the shell 4 of the casing. A dial glass or crystal 16 is placed 35 over the dial with the edge of the crystal fitting the inside of the flange 14 of the dial. The crystal 16 is curved to clear the hands of the clock and the edge only of the crystal rests on the dial. The forward end of the 40 shell 4 of the casing extends a distance beyond the edge of the crystal and is turned inwardly to provide an annular semi-cylindrical bead 20, whose edge forms a flange 45 engaging the margin of the crystal to co-

operate with the dial and its flange to hold the crystal in place.

It will be apparent that with this construction the curved crystal is firmly and securely held in place without use of a spacing ring or dial mat; that the marginal portion of the crystal is well protected by the semi-cylindrical bead 20; that the hands and numbers on the dial are visible at a greater angle than is possible where a flat crystal and spacing ring or dial mat is used; and that the crystal may be easily removed and replaced by merely loosening the screws 7 and removing the shell 4 of the casing.

What I claim is:

1. A clock of the class described having, in combination, a clock case, a dial, means passing through the wall of said casing for holding the dial in place within said casing, a curved crystal having its edge positioned against the dial, said clock casing having its front end extended beyond the edge of the crystal and turned inwardly to form an integral bead having its edge engaging the margin of the crystal to cooperate with the dial to hold the crystal in place.

2. A clock of the class described having, in combination, a dial having a forwardly extending peripheral flange, means for holding the dial in place, a curved crystal having its edge positioned inside of said flange and substantially fitting the flange, and a clock casing having its front end extending beyond the edge of the crystal and turned inwardly to form a bead having its edge engaging the margin of the crystal to cooperate with the dial to hold the crystal in place.

3. A clock of the class described having, in combination, a clock case, a dial, means for holding the dial in place within said casing, and a curved crystal positioned over the dial and engaged thereby, said clock casing having an inwardly turned flange on its forward end engaging the margin of the crystal to cooperate with the dial to hold the crystal in place.

CHARLES E. WILLIAMS.
